UNITED STATES PATENT OFFICE.

LEONARD D. GOFF, OF THREE RIVERS, MICHIGAN, ASSIGNOR TO ARMSTRONG
MACHINE WORKS, OF THREE RIVERS, MICHIGAN.

STEAM TRAP.

Application filed August 29, 1922. Serial No. 584,981.

To all whom it may concern:

Be it known that I, LEONARD D. GOFF, a citizen of the United States, residing at Three Rivers, county of St. Joseph, State of Michigan, have invented certain new and useful Improvements in Steam Traps, of which the following is a specification.

This invention relates to improvements in steam traps.

10 The object of the invention is to provide in connection with a float steam trap an improved means of insuring the discharge of air from such a trap and at the same time insure that the steam shall be trapped.

15 The invention in its principal form is an improvement and addition to the structure of the Patent No. 1,309,604, issued to Adam E. Armstrong, dated July 15, 1919. The invention is, however, adapted for use on 60 steam traps generally.

20 Objects pertaining to details and economies of construction and operation will definitely appear from the detailed description to follow.

25 I accomplish the objects of my invention by the devices and means described in the following specification. The invention is clearly defined and pointed out in the claims.

30 A structure which is a preferred embodiment of my invention is clearly illustrated in the accompanying drawing, forming a part of this application, in which:

35 Fig. I is a detail vertical sectional view through a steam trap embodying the features of my invention, showing the compound float and lever construction of the said Patent No. 1,309,604, with my improvements added thereto.

40 Fig. II is an enlarged detail vertical sectional view on a line corresponding to line 2-2 of Fig. I, showing the particular arrangement and disposition of my addition to such structure and illustrating the action thereof by dotted lines.

45 Fig. III is a plan view of one of the thermostatic metal strips made use of by me.

50 Fig. IV is a detail view of my improvements as applied to a simpler form of steam trap, the upper portion being in section to show details.

55 Fig. V is a plan view, slightly enlarged, of the float and valve of such simpler and modified form.

Fig. VI is a detail view of my invention as applied to an ordinary sealed float trap.

Fig. VII is a similar detail sectional view showing the same applied to another form of steam trap which is in commercial use 60 in which the float is open at the top.

In the drawing similar reference numerals refer to similar parts throughout the several views and the sectional views are taken looking in the direction of the little arrows 65 at the ends of the section lines.

The parts of the drawing will be designated by their numerals of reference.

1 is the outer shell of my improved steam trap provided with a cover at the top 2 secured thereto in any usual well-known manner. 3 is the intake and 4 is the discharge therefrom. 5 is the inverted cup or bell. 9 and 10 are bracket arms within the casting to which are connected the compound lever 11 which connects the inverted cup float 5 to the valve 6. 7 is the seat for the valve and 8 is the valve casing, the valve stem 61 being of squared or cruciform cross section. Between the valve casing 8 and the lever connection I interpose two blades of thermostatic metal 12 and 13 having a square hole 62 at the center which engages the valve stem 61. These pieces of metal 70 may be coupled together at their opposite ends loosely by cotter pins 14, though such cotter pins are merely a matter of convenience for assembling and could, of course, be the exclusive means if the center holes in the thermostatic metal plates were 75 round. The blades 12 and 13 when cold are curved, as indicated by full lines in Fig. II. When they become heated as by steam or hot water they collapse to the position indicated by the dotted lines in Fig. II.

80 The thermostatic metal made use of is a metal or material made up of layers of metal or material having different coefficients of expansion.

85 A consideration of the operation of the structure will show definitely what is accomplished and the cooperating relation of the different parts.

90 The bucket or float 5 hangs with its open end down directly over the inlet 3 which is centrally located in the bottom of the trap 1. The outlet of the trap 4 is at the top and therefore the body of the case must be full of water before any flows out.

95 With the bucket or float 5 in its lowest po- 110

sition the valve is open and water entering the trap flows into the open end of the bucket or float, then all around the bottom and up through the valve. This will occur 5 so long as water enters the trap. When the system is drained of water steam enters the trap and will rise into the bucket or float displacing the water which will flow out of the discharge. Steam will accumulate in 10 the bucket until the bucket becomes buoyant when it will quickly rise and close the valve, preventing a further discharge. The bucket is so weighted that it will float when about three-quarters full of steam.

15 When the valve is closed the body of the trap is full of water and, the bucket containing steam, nothing can enter the trap until the volume of the contents is reduced. This occurs by the condensation of steam in the 20 bucket. When the steam condenses its volume becomes smaller and either steam or water enters the trap to take the place of the steam condensed.

If steam enters it merely rises in the 25 bucket, taking the place of the condensed steam, and the valve is not opened. If water enters it takes the place of the condensed steam and thus the volume of the steam in the bucket becomes smaller. As this volume 30 reduces the buoyancy of the bucket becomes less until finally the volume of steam becomes so small that its buoyancy is overcome by the weight of the bucket which sinks to the bottom. It then acts through the compound lever and pulls the valve from its 35 seat, when the water will be quickly discharged until steam enters when, of course, the float will again become buoyant and close the valve.

40 This is the ordinary cycle of operations but oftentimes air in considerable volume is present in the system or in the trap and of course until the steam or hot water enters the same is comparatively cool. It is desirable that this air should escape. I, therefore, interpose the curved thermostatic plates 12 and 13 and they are of sufficient strength to hold the float down until they 45 are acted upon by the heat of the steam or hot water. When they become heated they collapse together into the position indicated by dotted lines in Fig. II, and the trap operates in the usual manner.

50 Cold air and cold water are allowed to escape until steam enters the trap. The float or bucket 5 has a small vent perforation 51 in the top which insures the discharge of air from the float and also permits a small quantity of steam to escape which, however, is 55 condensed by the cooler water.

60 I have described the preferred form but it is clear that the simplest form of float valve in which no lever connection is provided for actuating the valve can be operated in this way.

In Fig. IV, I illustrate such a structure, where the valve is connected directly to the top of an inverted bucket or bell 19, the valve 20 seating at 21, all within the outer casing 22, which is provided with an inlet 70 23 and a discharge 24. A strip of thermostatic metal 201 is disposed across the top of the float and remains in the position indicated by full lines until the heat of the steam distorts it, permitting the valve 20 to seat. 75 The plan of the float of this structure appears in Fig. V where the vent 19' and position of the valve 20 are indicated.

In Fig. VI, I show the principle applied to an ordinary sealed float valve. The float 80 15 is supported on a strip of thermostatic metal 16 secured at 17 to the bottom of the case 18. This metal is of such a character that when it is heated it is deflected to the position indicated by the dotted lines and 85 the float allowed to drop and thus close the valve.

In Fig. VII, I show the same applied to a well-known design of steam trap in which a 90 bucket is provided to receive the water and the weight of the water opens the valve to permit the discharge of the water. I here hold the bucket 30 in a depressed position by a strip of thermostatic metal 31 rigidly secured at 32 to the pipe leading from the 95 valve, these parts being disposed within the main casing 33. These are well-known forms of construction and are illustrative of the broad principle that I have developed.

Having thus described my invention, what 100 I claim as new and desire to secure by Letters Patent, is:

1. In a steam trap, the combination of a main casing, an outlet valve therefor, an inverted bell-shaped float with a small vent in 105 its top, a compound lever means connecting the said valve to the said float, and opposed pieces of thermostatic metal disposed within the casing in position to hold the valve depressed and open until acted upon by heat whereby the valve acts to close the discharge in a normal manner when heated and also is held in open position when cold and until the parts become heated thus insuring the discharge of water and air, coacting as specified. 110

2. In a steam trap, the combination of a main casing, an outlet valve therefor, an inverted bell-shaped float with a small vent in 115 its top connected to actuate said valve, opposed pieces of thermostatic metal disposed within the casing in position to hold the valve depressed and open until acted upon by heat whereby the valve acts to close the discharge in a normal manner when heated and also is held in open position when cold and until the parts become heated, thus insuring the discharge of water and air, coacting as specified. 120

3. In a steam trap, the combination of a 130

main casing, an outlet valve therefor, an inverted bell-shaped float with a small vent in its top connected to actuate said valve, thermostatic metal disposed within the casing 5 and arranged to act upon the said valve mechanism to hold said valve in open position until heated whereby the valve acts to close the discharge in a normal manner when heated and remain open when cold, thus insuring the discharge of water and air, coacting as specified.

4. In a steam trap, the combination of a main casing, a valve therefor, an inverted bell-shaped float with a small vent in its top, 15 compound lever means connecting the said valve to the said float, thermostatic metal disposed within the casing and arranged to act upon the said valve mechanism to hold

said valve in open position until heated whereby the valve acts to close the discharge 20 in a normal manner when heated and remain open when cold, thus insuring the discharge of water and air, coacting as specified.

5. In a steam trap, the combination of a 25 main casing, an outlet valve therefor, a float controlling the said valve suitably connected thereto, thermostatic metal disposed within the casing and arranged to act upon the said valve to hold it in open position against the 30 action of said float while cold and to allow the valve to close the discharge when heated, as specified.

In witness whereof I have hereunto set my hand.

LEONARD D. GOFF.
